UNITED STATES PATENT OFFICE.

GEORGE F. A. OCHS, OF NEWARK, NEW JERSEY.

TRACK TOOL.

Application filed January 27, 1926. Serial No. 84,198.

The purpose of the invention is to provide a tool particularly adapted for connection with the rail and tie to hold the latter and the base of the rail in tight contact during the spike driving operation; to provide a construction whereby the insertion or driving of the spike into the tie is accomplished by a gradual pressing movement rather than by impacts as when a maul is used; to provide a construction wherein the spike inserting elements are guided so that there may be no tendency to lateral movement likely to deflect the spike and bend the same or split the tie; and to provide a construction of simple form and in which the number of parts are few as compared with the functions performed, so that the invention may be cheaply manufactured and marketed at low cost.

With this purpose in view, the invention consists in a construction and combination of parts of which a preferred embodiment is illustrated in the accompanying drawings, wherein:

Figure 1 is an elevational view, partly in section, showing the invention applied in operative position for the insertion or extraction of spikes.

Figure 2 is a side elevational view.

Figure 3 is a top plan view.

The body 10 which, when the device is in use, seats upon the ball of the rail 11, is maintained in position against lateral movement on the rail by means of the depending ears 12 formed as integral parts of the body and abutting the rail tread on opposite sides. The body is hollowed out, as indicated at 14, to reduce its weight but what loss of strength is occasioned by this is compensated for by the webs 15 extending from an intermediate point in the height of the body to the forward and rear extremities of the foot 16 which carries the ears 12 and provides the seat for engagement with the rail tread.

The body is provided with lateral extensions 17 at an intermediate point in its height and with similar extensions 18 at the foot, the latter extensions acting as guides for the shanks 19 of the spike extracting elements which terminate in spike claws 20. The claws are adapted to engage underneath the head of the spike (indicated at 21) to withdraw it in the upward movement of the shank 19, or to bear upon the head and insert the spike in the depression or lowering of the shank 19. The claw 20 is pivotally connected with the shank by means of a pin

22 spanning the lower bifurcated portion of the shank which it pivotally engages as well as pivotally engaging a tongue 23 on the claw which is disposed in the fork or bifurcation of the shank.

The pivotal connection between the claw and the shank provided by the pin 22 provides for swinging movement of the claw toward and away from the rail, which is necessary to permit the claw to be disengaged from and engaged with the spike, as no movement of the shank 19 is possible in its guide. In operation, the shank 19 always moves in a plane parallel with the vertical plane of the rail and the spike being started properly, the inserting movement is always axially of the spike. Turning movement of the shank 19 in its guide in the extension 18 is precluded by a screw 24 threaded in the end of the extension and provided with a pilot 25 at its inner end which engages in a key-way 26 in the shank.

The extension 17 on the body member are bored in axial alignment with the guide 80 openings in the extension 18 and interiorly threaded for the reception of the screws 27. The screws at their lower ends have pivotal connections with the shanks 19 each of which consists of a diametrically reduced extension 28 which enters a socket in the upper end of the shank. This pivotal connection is maintained against separation axially by means of radial screws 29 threaded through the shank with their terminals 30 engaged in a circumferential slot 31 formed in the extension 28. The setting of the screws 29 is maintained by lock nuts 32. The upper terminal of the screw 27 is provided with a wrench seat 33, so that any acceptable form of wrench may be engaged therewith and the screw rotated in either direction to raise or lower the shank 19 and therefore withdraw or insert a spike with which the claw 20 is engaged.

The body is secured in position on the rail for the spike inserting or extracting operation by means of stirrup arms 34 arranged in pairs disposed at opposite ends of a cross-head 35. The stirrup arms are pivotally connected with the cross-head on reduced extensions 36 at opposite ends of the latter, being secured in place by nuts 37 threadingly engaged with the extensions, washers 38 being interposed between the nuts and the stirrup arms. The stirrup arms at their lower ends are provided with hooks 39 of which

those of each pair are turned inwardly towards each other. These hooks 39 are adapted for engagement with the under face of a tie 40 and, when the cross-head is elevated with respect to the body, the stirrup arms are brought into firm engagement with the tie and thus the rail and tie are clamped together and the body secured in position on the tread of the rail, since the cross-head is connected with the body by means of a screw 41 which threadingly engages a centrally disposed axial bore 42 in the body.

Since angular or turning movement of the cross-head with respect to the body must be prevented, pivotal connection between the screw 41 and the cross-head is provided. The screw, therefore, is formed with an integral collar 43 abutting the cross-head on the under face, the shank 44 extending through the cross-head and receiving above the latter a nut 45 between which and the cross-head is interposed a washer 46. The shank in the region of the nut is threaded for the reception of the latter and above this threaded portion a wrench seat 47 is formed, so that an appropriate tool may be used for rotating the screw and thus elevating the cross-head with respect to the body and therefore firmly mounting the device in position on the rail and securing the latter and the tie together, so that the spike inserting and extracting operation may be performed by the actuation of the screws 19.

The invention having been described, what is claimed as new and useful is:—

1. A track tool comprising a body having a forwardly and rearwardly extending foot portion provided with depending ears defining with the foot portion a seat for engagement with the tread of a rail, tie engaging means operatively connected with the body, means for effecting relative movement between the body and the tie engaging means to bring the tie and the rail base into firm contact, said last named means comprising a screw threadingly engaged with the body, and a cross-head by which the tie engaging

means are carried, said screw being formed with an integral collar abutting the under face of the cross-head and having a shank above said collar pivotally engaging the cross-head, and a nut and washer carried by the shank portion above the cross-head.

2. A track tool comprising a body having a seat at its lower end for engagement with the tread of a rail, tie engaging means carried by said body, means for adjusting the tie engaging means with respect to the body to force a tie and the base of an engaged rail into firm contact, the body having lateral extensions at an intermediate point and at its lower end, a spike extracting and inserting element carried by and guided by said extensions, said spike extracting and inserting element comprising a shank slidably mounted in the lower of said extensions and provided at its bottom end with a claw, and a screw threadingly engaged with the upper of said extensions and having a pivotal connection at its lower end with said shank.

3. A track tool comprising a body having a seat at its lower end for engagement with the tread of a rail, tie engaging means carried by said body, means for adjusting the tie engaging means with respect to the body to force a tie and the base of an engaged rail into firm contact, the body having lateral extensions at an intermediate point and at its lower end, a spike extracting and inserting element carried by and guided by said extensions, said spike extracting and inserting element comprising a shank slidably mounted in the lower of said extensions and provided at its bottom end with a claw, a screw threadingly engaged with the upper of said extensions and having a pivotal connection at its lower end with said shank, and means to preclude angular or turning movement of the shank, said claw having a pivotal connection with said shank.

In testimony whereof he affixes his signature.

GEORGE F. A. OCHS.
